UNITED STATES PATENT OFFICE.

WILLIAM B. ERB, OF CHICAGO, ILLINOIS.

DOUBLE-ACTING DEEP-WELL PUMP.

SPECIFICATION forming part of Letters Patent No. 763,664, dated June 28, 1904.

Application filed June 8, 1903. Serial No. 160,454. (No model.)

To all whom it may concern:

Be it known that I, WILLIAM B. ERB, a citizen of the United States, residing at Chicago, in the county of Cook and State of Illinois, have invented new and useful Improvements 5 in Double-Acting Deep-Well Pumps, of which the following is a specification, reference being had to the accompanying drawings, forming a part thereof.

10 The purpose of this invention is to provide an improved double-acting pump for deep wells, its specific features being designed to afford maximum capacity within a given bore.

15 It consists of the construction and specific features which are set out in the claims.

In the drawings, Figure 1 is an axial section of the portion of pump-barrel containing the features constituting my invention. Fig. 2 is a transverse section at the line 2 2 on 20 Fig. 1. Fig. 3 is a section at the line 3 3 on Fig. 1.

The barrel 1 of my improved pump is designed to be in exterior diameter of the full interior diameter of the well-casing, and all the 25 couplings and connections are therefore kept within that diameter. The structure is such that I can employ for this barrel standard brass tubing, into the upper and lower ends of which there are screwed the terminal fittings 2 and 3, respectively. The lower fitting 3 comprises a valve-seat 4 and a cage 5 above, it defining what may be termed the "valve-chamber"—i. e., the space within which the valve 7 may move while being retained in proximity to its seat 4. The upper fitting 2 has screwed into its lower end a valve-seat 6, and the cavity of the fitting above said seat constitutes a chamber for a valve 8, lodged therein. The valve 7 is designed to be introduced laterally under the cage 5 before the fitting is screwed into the barrel 1, and the valve 8 is to be introduced into its chamber through the lower end of the fitting 2 before the seat 6 is screwed in. Said fitting 2 may 35 have a bridge 9 above the valve and check the movement of the latter away from the seat. In the barrel between the two valve-chambers thus located near the opposite ends there is placed the piston 10, having suitable packing- 40 rings 10^a. The piston has toward its upper

and lower ends, respectively, valve-chambers comprising the valve-seats 11 and 12 and above the seats, respectively, in the chambers are the valves 13 and 14, seating downward on their respective seats. Extending 55 through the piston from the lower valve-chamber to the upper valve-seat are two non-communicating passages 15 and 16, respectively, the particular form of which will be hereinafter described. A tube 17 extends 60 down through the valves 8 and 12 and their chambers and seats, respectively, and is connected to the piston at the upper end of the duct or passage 16, and thereby becomes a stem for the piston, by which it may be operated up and 65 down in the barrel 1. A tube 18 is similarly extended up through the valves 7 and 14 and their seats, respectively, and connected into the lower end of the passage or duct 15, and is thereby carried with the piston in its vertical reciprocation in the barrel. The lower end of the tube 18 is open in the water-supply and may be guarded by the perforated tube 20, screwed into the lower end of the fitting 3 and operating as a strainer to exclude sand both from 70 the barrel and from the tube 18. The upper end of the tube 17 above the valve 8 is perforated, as seen at 21, to afford communication from its interior out into the uptake-pipe 22, which is screwed into the upper end 75 of the fitting 2 and constitutes the upward continuation of the barrel for conducting the water upward to the discharge-spout. To the upper end of the tube 21 there is connected by the coupling 23 the pump-rod 24, which is 80 preferably hollow, and thereby constitutes a continuation of the tube 17.

The operation of this structure is as follows: When the pump-rod is depressed, carrying the piston downward in the barrel 1, 90 the valve 8 is seated, and a tendency to vacuum is caused in the barrel above the piston, causing the water to pass up through the tube 18 and passage 16, lifting the valve 13 and occupying the space in the barrel above the piston. At the same time the valve 7 is seated and the water (which, as will be seen in its operation, occupies the barrel below the piston) is forced up past the valve 14 through the piston 16 and into the tube 17. When 95 100

the stroke is reversed, the piston is lifted and valve 13 is seated, and the water in the barrel above the piston is lifted out through the valve-seat 6 past the valve 8, which is lifted 5 from its seat by such movement of the water, and passes out from the upper end of the fitting 2 into the uptake-pipe 22. Simultaneously a tendency to vacuum is caused in the barrel below the piston, the valve 14 being seated and the valve 7 lifted, drawing water in from the supply through the valve-seat 4 and occupying the chamber of the barrel below the piston. Eventually it will be seen that the water taken in through the low stem 17 will be delivered through the 15 perforations 21 or upper end of that stem out into the uptake-pipe, so that by both movements of the piston water will be discharged into the uptake-pipe and eventually delivered 20 from the top thereof in a continuous stream, the supply being obtained equally from the up and down strokes of the piston.

The specific construction of the piston, by which the two end connecting-passages 15 and 25 16 are formed through it, is preferably such as cause each passage to terminate centrally with respect to the barrel at the end at which it is to have the tube connection described. This is most conveniently effected by casting 30 the middle element of the piston as two concentric cylinders A and B, joined by vertical webs *a* and *b* at diametrically opposite positions, and by transverse semi-annular webs *a'* and *b'* at the upper and lower ends, respectively, one at one side and the other at the other side of said longitudinal webs *a* and *b*, the interior cylinder A having a transverse diaphragm A' midway in its length and being cut away between that diaphragm and the 35 semi-annular web *b'* at the lower end for communication with the semi-annular space outside of said interior cylinder and being cut between said diaphragm and the upper semi-annular web *a'* for like communication with 40 the other semi-annular space corresponding to said semi-annular diaphragm. These semi-annular spaces, together with the portions of the interior cylindrical cavity above and below the transverse diaphragm, constitute, as 45 will be seen, the passages 16 and 15, respectively.

As a convenient means of construction I prefer to make the end portions of the piston comprising the seats and chambers of the valves 50 13 and 14, as illustrated, in separate pieces from said middle portion of the piston and screwed thereonto. Said middle portion has, preferably, an annular flange *c* at the middle point of its length, whose exterior diameter 55 is fitted to the interior diameter of the barrel 1, and onto the said middle portion at opposite sides of this annular flange there are passed metal rings *d d* before the end portions comprising the valve seats and chambers 60 65 are screwed on, and between said metal rings

and the annular flange on one end and the terminal elements comprising the valve seats and chambers on the other end there are introduced suitable rings 10^a, of packing material, which, it will be noted, are adapted to be expanded for tight fitting in the barrel by the screwing up of the terminal elements on the middle element of the piston. 7c

I claim—

1. A double-acting pump comprising a barrel having toward each end a valve-seat, valve-chambers above said seats respectively, and downwardly-seating valves therein; a piston playing in such barrel between such valve seats and chambers, said piston having two 80 non-communicating ducts extending longitudinally therein, one duct opening at one end centrally with respect to the piston, and the other duct opening centrally with respect thereto at the other end; tubes connected to 85 the piston at said central openings of the ducts and extending therefrom respectively upward and downward; valve-chambers at the opposite ends of the piston surrounding the tubes respectively, said ducts opening into said 90 chambers respectively; downwardly-seating valves in said chambers, and connections from the upper end of the upper tube for reciprocating the piston.

2. A double-acting pump comprising a barrel having at its upper and lower ends respectively valve-seats and upwardly-opening valves thereabove, a piston between said valve-seats having at its upper and lower ends valve-seats and upwardly-opening valves thereabove 100 respectively, said piston having extending between said valve-seats two non-communicating ducts, one opening centrally with respect to the barrel at the upper end, and the other opening centrally with respect to the barrel 105 at the lower end; tubes extending through the valve-seats in said piston and connected into said central upper and lower ends of said ducts respectively, the upper tube being open above the valve at the upper end of the barrel, 110 and the lower tube being open below the valve at the lower end, and connections for reciprocating the piston in the barrel.

3. In a double-acting pump the combination 115 with a barrel having at its upper and lower ends valve-seats and valves thereabove seating downwardly; tubes extending centrally within the barrel and affording guidance for said valves in their movements with respect to their seats; a piston between the valve-seats 120 having itself toward its upper and lower ends valve-seats and valves seating downward thereon, said tubes being extended through said valve-seats and valves, and connected to the piston, and affording guidance for the 125 valves thereon; said piston having two non-communicating ducts connected with said tubes respectively at opposite ends, and at their other ends communicating respectively with the openings through the valve-seats. 130

4. In a double-acting pump a piston having concentric cylindrical elements, A and B, longitudinal webs, *a* and *b*, joining said concentric cylinders and partitioning the annular space between them; the central cylinder having a transverse diaphragm, A', the semi-annular partitioned intervals between said concentric cylinders being closed, one at the top and the other at the bottom, by the webs, *a'*, *b'*, the inner cylinder being cut away laterally above the transverse diaphragm for communication downward with the semi-annular space at that side, and being cut away below said transverse diaphragm laterally for communication upward with the other semi-annular space.
5. In a double-acting pump, in combination with the barrel having at its upper and lower ends valve-seats and valve thereabove seating downwardly, the piston between said valve-seats having two non-communicating ducts extending through it, one opening centrally at the upper end and the other opening centrally at the lower end; tubes connected to said centrally-opening ends of the ducts respectively, and extending respectively upward and downward through the upper and lower valve-seats of the barrel for guiding the piston and conducting the water through the valve-seats; valves which control said piston-ducts respectively, both opening upward, the valves at the upper and lower end of the barrel being annular in form and centered and guided on the tubes respectively; terminal junction-fittings for the upper and lower ends of the barrel secured thereto by insertion therein, and having said seats for said valves respectively and provided with means for checking the movement of the valves away from their seats.
6. In a double-acting pump comprising a barrel having toward each end an annular valve-seat and a valve-chamber thereabove; a piston playing in such barrel between the valve seats and chambers and having tubular stems extending from the opposite ends through the centers of said valve-seats respectively; annular valves lodged in said chambers above said valve-seats respectively, and carried and guided on said tubular stems of the piston, the piston having a cavity at each end through which the tubular stems extend, rendering said cavities annular, and having non-communicating ducts, each of which at one end communicates with the said annular cavity at that end of the piston, and at the other end leads into the open end of the tubular stem connected to the piston thereat; valve-seats which form respectively the lower and upper boundaries of said lower and upper cavities respectively, and annular valves mounted and guided on said stems above said valve-seats respectively.
7. A double-acting pump comprising a barrel having toward each end a valve-seat and a valve seating downwardly thereon; a piston in said barrel between the valve-seats having tubular stems extending through the seats, said piston having a cavity at each end through which the tubular stems extend rendering said cavity annular, and having non-communicating ducts, each of which at one end communicates with the said annular cavity at that end of the piston, and at the other end leads into the open end of the tubular stem connected to the piston thereat; valve-seats which form respectively the lower and upper boundaries of said lower and upper cavities respectively, and annular valves mounted and guided on said stems above said valve-seats respectively.
8. In a double-acting pump comprising a barrel having toward each end a valve-seat and a valve-chamber thereabove, a piston playing in such barrel between the valve seats and chambers and having tubular stems extending from the opposite ends through the centers of said valve-seats respectively, such piston comprising an integral metal body to which the tubular stems are directly connected, and having cavities at each end through which the tubular stems extend to make junction with said body, and having non-communicating ducts, each of which at one end communicates with the cavity at that end of the piston, the tubular stem from the other end being connected to said body by being screwed into the other end of such cavity; valve-seats forming respectively the lower and upper boundaries of said lower and upper cavities respectively, and valves mounted and guided on the tubular stems above said valve-seats respectively.

In testimony whereof I have hereunto set my hand, in the presence of two witnesses, at Chicago, Illinois, this 3d day of June, A. D. 1903.
